[57] CLAIM

The ornamental design for a sculpture, substantially as shown.

DESCRIPTION

FIG. 1 is a top plan view of a sculpture showing my new design;

FIG. 2 is a front elevational view of the sculpture shown in FIG. 1;

FIG. 3 is a rear elevational view showing my new design opposite to that shown in FIG. 2; and

FIG. 4 is a bottom plan view of the sculpture shown in FIG. 1.
